UNITED STATES PATENT OFFICE

LORN CAMPBELL, JR., OF LAKEWOOD, OHIO

VALVE FOR MEASURING AND DISPENSING FLUID

Application filed May 17, 1928. Serial No. 278,470.

This invention relates to valve means for measuring and dispensing fluids. In some of its more limited applications it relates to the dispensing of gas charged carbonated liquids and in others to the measuring of liquids which are not charged with a gas.

In the drawings accompanying and forming a part of this specification.

Figure 1 shows one embodiment of my invention in position on one form of receptacle.

Figure 2 is a side elevation view taken on line 2—2 of Figure 1;

Figure 3 shows the device of Figures 1 and 2 with clamping lever in position preliminary to the clamping operation.

Figure 4 is a side elevational view taken substantially on line 4—4 of Figure 1;

Figure 5 is a central sectional view taken on line 5—5 of Figure 1 with the parts shown 20 in their normal position on the receptacle;

Figure 6 is a view similar to Figure 5 but showing an embodiment of my invention modified as to certain parts;

Figure 7 is a view corresponding to Figure 5 but showing another modified embodiment of my invention;

Figure 8 is a view corresponding to Figure 5 but showing still another modified embodiment of my invention.

Referring first to Figures 1 to 5 inclusive, 30 1 designates a shouldered, stopper like, receptacle-sealing member in sealing position with the outlet opening or mouth of a receptacle 2. This member 1 is disposed in and 35 carried by a cap 3 provided with a clamping lever 4 pivoted thereto and having inturned projections 5 to engage with the underside of the shoulder 6 of the receptacle 2 and press the member 1 into position to close the outlet opening of the receptacle. The annular shoulder 7 on member 1 extends over the top surface of the shoulder 6 and additionally seals the receptacle. The lever 4 is provided 40 with a notch 8 in its lower end so that it may be used to open a receptacle, for example, to remove a crimped cap of the ordinary well known form.

A tube 9 closes at one end by a pressed in flattened plug 10 and carrying at its other 50 end a pressed on, chambered head 11 having

a knurled flange 12 extends slidably and rotatably through cap 3 and bore 50 of the member 1. The head 11 carries a pressed in tube 13 which communicates through the head 11 with the interior of the tube 9. Near the lower or inner end of the tube 9 an inlet opening 14 is formed laterally through the side wall of the tube, which opening is normally closed by the sealing member 1, the tube 9 being normally retained in the position shown in Figure 5 by reason of the spring 15 which is compressed between the head 11 and cap 3 about tube 9.

It will be understood that the tube 9 may be moved longitudinally through the cap 3 by exerting pressure on head 11 sufficient to compress the spring 15 as in Fig. 4 and also that it may be rotated in the cap 3, as indicated in Figures 1 and 3. The sealing member 1 is retained in cap 3 by the tube 9, plug 60 65 10 and spring 15.

As best shown in Fig. 5 the upper end of the bore 50 is enlarged to provide an annular recess 51. A relatively large annular recess 52 is provided in the intermediate portion of the bore spaced from the ends. The material intermediate the recesses is thus adapted to form an annular lip 53 in contact with the tube 9 the resilience of which is greater than the remainder of the member 1, and which is adapted to bend slightly in the direction of reciprocation of the member 9.

In using the device shown in Figures 1 to 5 the receptacle is first opened as by employing the notch 8 on lever 4 to remove the cap or other sealing means and then the sealing member 1 is inserted in the outlet opening of the receptacle and the device is pressed down substantially into the position shown in Figure 3 after which the lever 4 is brought down into the position of Figure 1 thereby forcing the sealing member tightly into the mouth of the receptacle. When liquids are to be measured the receptacle may be inverted and pressure is applied on the head 11 to expose the opening 14 to the liquid which will pass out through tubes 9 and 13. In this manner the liquid may be measured in drops, if desired. If necessary, air may 85 90 95 100

be admitted to the receptacle by returning the receptacle to its upright position and pressing down on head 11 to expose opening 14 below the member 1, and then more liquid withdrawn as just described. Where liquids are charged with gas, for example carbonated liquids, the liquid may be discharged from the receptacle under considerable force if, after the device is in the position shown in Figure 5 the receptacle is shaken and inverted and then the head 11 is pressed down to expose the opening 14 to the liquid.

As best illustrated in Fig. 5 the pressure that exists above carbonated beverages, is adapted to press the end of the plug 10, together with the tension exerted by the spring 15, against the bottom of the member 1 which being resilient is compressed and restricted by the wall of the container and is brought into fluid tight engagement with the outer wall tube 9 to assist in the sealing of the opening 14.

In the modification shown in Figure 6 the cap 3 carries a pivoted lever 16 the lower part of which lever is formed as a cork screw 17. The sealing member 18 which is carried by cap 3 is provided with an enlarged central recess 19 which is exposed to the contents of the receptacle. A tube 20 closed at its inner end by plug 24 projects from cap 3, has a head 21 at its outer end and a tube 22 communicating with tube 20 through the head. The head 21 is extended toward the cap 3 to form a partial housing for the spring 23 which surrounds the tube 20. The head 21 has a limited movement which, however, is sufficient to expose the lateral opening 24 through the tube 20 to liquid in the receptacle.

The embodiment of my invention shown in Figure 7 comprises a sealing member 25 in the form of a washer or gasket to cover the mouth of a receptacle. The gasket is carried by a cap 26 having an integrally formed depending flange 27 shaped to engage under the shoulder surrounding the mouth of the receptacle. This flange may extend for a considerable distance around the receptacle, if desired. A clamping lever 28 is pivoted to the cap 26 and has an arm 29 suitably disposed to engage under the shoulder of the receptacle and securely clamp cap 26 and gasket 25 on the receptacle. A tube 30 extends slidably and rotatably through the gasket 25 and cap 26 and is provided with a pressed on flattened plug 31 at its lower end, and a pressed on hollow head 32 at its upper end which head carries pressed therein the tube 33. A spring 34 serves to maintain the tube 30 in the position shown in this figure where the inlet opening 35 of the tube 30 is disposed in and closed by the gasket 25. The operation of this device is substantially the same as has been described hereinabove for other modifications.

65 The embodiment of my invention shown in

Figure 8 has a cap 36 provided with a threaded flange 37 to engage with a threaded split-ring 38 by means of which the device is secured to a receptacle. The cap 36 also has a lever arm 39 which may be used in screwing the cap 36 to the ring 38, the latter having a knurled edge which permits it to be held against rotation and the arm may be used in opening the receptacle, for which purpose it may be provided with a notch similar to notch 8 of Figure 2, or with a corkscrew such as is shown at 17 in Figure 6 or other suitable receptacle opening means. The tubes 40 and 41, plug 42 and head 43 and spring 44 are similar to the corresponding parts of Fig. 7.

It will be understood that the corkscrew 17 may be substituted for the corresponding lever and opener of any of the other figures and vice versa. The head 22 may likewise be substituted for the various heads of the other figures and vice versa.

The sealing members 1, 18, 25 and 36 may be made of rubber or other suitable material and the remaining parts may be made of any suitable metal.

Having thus described my invention so that others skilled in the art may be enabled to practice the same what I desire to secure by Letters Patents is defined in what is claimed.

What is claimed is:

In a fluid container, a dispensing opening therefor, a fluid dispensing device for said container comprising a cap, a bored sealing member, means to secure said cap and sealing member on said container, a valve disposed in the bore of said sealing member comprising a tube extending through said sealing member, a closure for the end of the tube adapted to engage the end of the sealing member to compress the same, valve parts adjacent the end of the tube adapted to be closed by the sealing member, the sealing member having a flexible internal annulus adapted to resiliently engage said tube in fluid tight engagement therewith.

In testimony whereof I hereinbelow affix my signature this eleventh day of May, 1928.
